DESIGN FOR A DISPLAY DEVICE

Robert C. Byler, Melrose Park, Pa.

Application September 5, 1942, Serial No. 108,144

Term of patent 8½ years

To all whom it may concern:

Be it known that I, Robert C. Byler, a citizen of the United States and a resident of Melrose Park, Montgomery County, Pennsylvania, have invented a new, original, and ornamental Design for a Display Device, of which the following is a specification, reference being had to the accompanying drawing, forming part thereof, in which—

Figure 1 is a front elevational view of the display device, showing my design; and
Figure 2 is a side elevational view thereof.

I claim:
The ornamental design for a display device,
substantially as shown.

ROBERT C. BYLER.
